J. S. STOKES,
SEALED WRAPPED PACKAGE,
APPLICATION FILED SEPT. 29, 1917.

1,382,752.

Patented June 28, 1921.

Inventor,
John S. Stokes
By his Attorneys,

Meyers, Cusman & Rea

UNITED STATES PATENT OFFICE.

JOHN STOGDELL STOKES, OF MOORESTOWN, NEW JERSEY, ASSIGNOR TO STOKES & SMITH COMPANY, OF SUMMERDALE, PHILADELPHIA, PENNSYLVANIA, A CORPORATION OF PENNSYLVANIA.

SEALED-WRAPPED PACKAGE.

1,382,752.

Specification of Letters Patent. Patented June 28, 1921.

Application filed September 29, 1917. Serial No. 193,930.

To all whom it may concern:

Be it known that I, JOHN STOGDELL STOKES, a citizen of the United States, residing at Moorestown, in the county of Burlington and State of New Jersey, have invented new and useful Improvements in Sealed-Wrapped Packages, of which the following is a specification.

This invention relates to certain novel and useful improvements in sealed wrapped packages.

In the present instance it is my purpose to so apply and secure a wrapper to a box or other container of goods, that a complete package results which is possessed of certain attributes and characteristics of both a tight-wrapped and loose wrapped package, that is to say, the wrapper proper will be adherently attached at certain points to certain sides or walls of the box so as to completely seal the same, while when desired, such wrapper may be readily torn loose or stripped from the box so as to permit the opening of the latter and access to the contents. Thus, while the goods, especially if of a perishable nature, or subject to deterioration under atmospheric influences, will be thoroughly sealed and protected from contamination and destruction, yet when desired, the wrapper may be instantly and readily stripped from the box shell to such an extent as to permit the opening of the latter.

Another object of the invention is the provision of a wrapped package of this character wherein the wrapper blank is so shaped, cut and applied to the box that a considerable saving of wrapper material is obtained in comparison with the ordinary wrapper blank commonly employed in connection with packages of this character, and which ordinary blank envelops the entire box. In my wrapped package the wrapper blank while covering the top, sides and ends of the box, does not completely cover or overlie the bottom part, and therefore, when the package is exposed to view in the usual manner, as on a shelf in a store, it will present the appearance of a completely wrapped package, the uncovered bottom section of course being concealed from view. The saving of material mentioned is an important factor where the wrapper blank is

of relatively expensive, transparent, or glacine paper, such as is much employed in 55 wrapping packages, such as cartons of cigarettes and similar merchandise, for considering the vast quantity of cartons so employed, the saving in the amount of glacine wrapper paper is an important item. It is 60 desirable, with cigarette cartons, food product packages and the like, to use this glacine paper because the trade-marks, brands and other printed matter usually applied to the outer faces of the cardboard cartons can be 65 inspected and observed through the glacine or transparent paper by the merchant and the purchaser, who can therefore tell at a glance whether or not the sealed wrapped box contains the goods or brand of goods 70 desired.

Another object of my invention is the provision of a sealed wrapped package of this character which will embody the desired features of neatness in appearance, 75 economy in the amount of material employed and in the cost of production.

With the above recited objects and others of a similar nature in view my invention consists in the construction, combination 80 and arrangement of parts set forth in and falling within the scope of the appended claims.

In the accompanying drawings:

Figure 1 is a plan view of a wrapper 85 blank employed in connection with my sealed wrapped package and indicating the marginal portions of the blank to which the adhesive for sealing the wrapper is applied.

Fig. 2 is a perspective view of a completely wrapped package.

Fig. 3 is a perspective view of a partially wrapped package and showing the manner in which the wrapper is sealed or adhesively secured to the bottom of the carton or box. 95

Fig. 4 is a transverse sectional view taken through a completely wrapped package such as is shown in Fig. 2.

Referring now to the accompanying drawings in detail, the letter A indicates the 100 wrapper blank as an entirety and this blank is preferably made from a sheet of thin, flexible, readily foldable material, such as glacine or transparent paper for with certain classes of packages, it is advantageous 105 to employ this transparent or glace paper

for the reasons before mentioned, but it will of course be understood that if desired, this wrapper may be made from paper not necessarily transparent, and should an opaque or 5 non-transparent wrapper blank be employed, the trade-marks, brands and the like may be printed on the outer face thereof. The body portion of the blank is preferably rectangular in form and is adapted to be folded along 10 the longitudinally extending parallel lines 1 to form the top section 2 and the side sections 3 of the wrapper. The top section 2 has integral therewith at opposite ends a pair of rectangular flaps 4 which are adapt- 15 ed to cover the ends of the box when the wrapper is applied, these end flaps being foldable on the lines 5. Each side section 3 of the wrapper is formed with a pair of end laps 6 foldable along the lines 7 and a 20 longitudinally extending marginal lap 8. As shown in Fig. 1, each of these marginal laps 8, is of shorter length than the length of the side sections to which it is united, or of which it forms a part, so that when the 25 wrapper is applied to the box and these laps 8 are folded against the bottom of the box, there will be sufficient room between the ends of these laps and the adjacent end edges of the box to accommodate the lapped 30 or folded free ends of the end flaps 4, as will be understood by reference to Fig. 3. Each of these marginal laps 8 is coated on one side with an adhesive as at 9, while each of the rectangular end flaps 4 is coated on 35 one face adjacent three marginal edges with an adhesive as at 10. If desired, a small amount of adhesive may also be applied to the laps 6, but this is not necessary, and therefore, it will be noted by reference to 40 Fig. 1 that the blank is not completely coated with an adhesive, the latter being only applied to the rectangular end flaps and to the longitudinal marginal laps 9. Thus when the wrapper is applied to the 45 box it will not be adhesively attached to all of the walls thereof, as is customary with tight-wrapped packages, nor yet will it be free from all of the walls, as is the practice in making certain types of loose-wrapped 50 packages, but it will be free from some of the walls and adhesively attached at certain points to other walls. The manner of applying the wrapper to the box will best be understood by reference to Figs. 3 and 4. 55 The letter B indicates a box which in the present instance is in the form of two telescoping box-shells, such as usually make up a carton for holding packs of cigarettes and the like. In the application of the wrapper 60 the blank is placed on a suitable support with the adhesive face uppermost and the box, bottom up, is placed on the blank so that the top wall of the box will rest upon or overlie the top section 2 of the blank. 65 The side sections 3 of the blank are now

bent up against the side walls of the box and the longitudinal marginal laps folded inward against the bottom of the box and adhesively secured thereto by the strips of adhesive 9, as will be understood by reference to Fig. 3. The end laps 6 of the side sections 3 of the wrapper blank are now folded in against the ends of the box, but, lacking adhesive in the present instance are not secured thereto. The end flaps 4 of the 70 blank are now folded inward against the ends of the box and are adhesively attached to the outer faces of the end laps 6, and then the box is finally and completely wrapped and sealed by folding the remaining adhesively coated marginal edges of the end flaps 4 inward and downward against the bottom of the box, the adhesive of course causing the end flaps to adhere to the bottom of the box. Thus the box will be completely and securely sealed against the entrance of air, foreign matter, such as dust, dirt and the like, and the contents will be preserved against deterioration. At the 75 same time, the wrapper, while securely attached by the adhesive to the box, will not be adherently attached to the latter at all the walls of the same so that when desired, the wrapper may be readily stripped or torn off from the box to permit the latter 80 to be opened by removing the cover and thus give access to the contents. The completely wrapped package will appear as shown in Fig. 2, when exposed for sale in the usual manner, and in the present instance, the wrapper represented is of the transparent or glacine paper hereinbefore 85 mentioned, so that the markings, coloring matter and the like of the box will appear and be readily observable through this transparent paper. 90

In comparison with the ordinary form of completely wrapped box or package, it will be seen that with each box I accomplish a saving of a strip or piece of wrapper paper 110 almost equal in area to the area of the bottom of the box, and this is an exceedingly important factor in the economical production of the wrapped package, especially when the present high cost of this wrapper 115 paper is taken into consideration.

Furthermore it will be noted that as the trade-marks, brands and other advertising matter is printed on the face of the cardboard carton, the removal of the glacine 120 wrapper will not result in the obliteration of such marking, as is the case where the printing is on a removable wrapper covering a plain box.

While I have herein shown and described 125 one particular embodiment of my invention, I wish it to be understood that I do not confine myself to all the precise details of construction herein set forth by way of illustration, as modification and variation may 130

be made without departing from the spirit of the invention or exceeding the scope of the appended claims.

What I claim is:

- 5 1. A sealed wrapped package comprising a box-like container and a wrapper therefor, said wrapper comprising a top portion, end portions integrally connected thereto, and integral side portions having extensions adhesively attached to the adjacent parts of the end portions, said top, side and end portions being entirely free from the underlying package and having extensions at their outer edges overlying and attached to the 15 marginal portion only of the bottom of the package.
- 10 2. A package comprising a box-like container and a unitary sheet wrapper having edge portions adhesively attached to the margins of the bottom of the container, forming a substantially continuous joiner between the wrapper and the container, the 20 wrapper being shaped to leave the remaining interior area of the bottom free of 25 wrapping, the wrapper covering all the

other faces of the container and being entirely unconnected thereto, certain narrow marginal portions of the wrapper being adhesively connected to each other at the ends of the container to complete the substantially dust- and moisture-proof inclosure of the container. 30

3. A package comprising a box-like container and a wrapper consisting of a single sheet of transparent paper completely surrounding and inclosing the container, except one side thereof, the wrapper being entirely unattached to the container except on said side, the wrapper having edge portions adhesively secured to said side about the 40 marginal outline thereof, leaving the central area of said side uncovered by the wrapper, certain other narrow marginal portions of the wrapper being adhesively secured together to complete the substantially dust- 45 and moisture-proof inclosure of the container.

In testimony whereof I have hereunto set my hand.

JOHN STOGDELL STOKES.
